COMPRESSOR

Chester E. Curry, Muncie, Ind.

Application September 4, 1941, Serial No. 409,465

7 Claims. (CL 230—139)

This invention relates to improvements in compressors, and it has special reference to a machine of this kind which is more particularly intended for the compressing of refrigerants, and suitable for household refrigerators wherein the machine must work for long periods without attention, and at sustained high efficiency.

To provide improvements resulting in a compressor which is economical of manufacture and operation, and is durable and dependable, is the object, broadly stated, of my invention. This general object, as well as other and more specific aims, as will presently appear, are accomplished by, and my invention is embodied in the new construction, combination and arrangement of parts described in the following specification and illustrated in the accompanying drawings.

The several parts of the invention, are identified by suitable characters of reference applied to them, in the different views in the drawings, in which—

Figure 1 is a side view of my improved compressor, portions of the casing being broken away, and portions of some of the operative parts being broken away.

Figure 2 is an end view, in the direction of arrow 2, and on the broken line 2—2, in Figure 1.

Figure 3 is a top plan view, in the direction of arrow 3 in Figure 1, portions of the casing being broken away.

Figure 4 is a vertical cross section view, taken on the broken line 4—4, in the direction of arrow 4 in Figure 1.

Figure 5 is a perspective view of the vane, removed.

Figure 6 is an enlarged vertical central longitudinal sectional view, taken on the broken line 6—6, in the direction of arrow 6 in Figure 3, with the vane shown in elevation.

Figure 7 is an end view of the cylinder, as seen in the direction of arrow 7 in Figure 6, the arbor member being shown in cross section.

Figure 8 is a view looking downwardly (see arrow 8) on the structure shown in Figure 6, the fixed central member or arbor being shown in elevation, and the parts adjacent thereto being shown in cross section.

Figure 9 is a diagrammatic view showing the position of the crescent shaped working cavity (the direction of its travel being, indicated by the arrow) when it will have arrived at the end of its stroke. Stroke, meaning, the travel of the said cavity through three hundred sixty degrees.

Figure 10 is a diagrammatic view showing the position of the cavity, at one fourth of its stroke.

Figure 11 is a diagrammatic view showing the position of the cavity at one half of its stroke.

Figure 12 is a diagrammatic view showing the position of the cavity, at three fourths of its stroke.

The power unit is an electric motor, comprising in its structure, the usual field assembly A and the rotor B.

A casing structure within which the several operative parts of my improved compressing machine are enclosed, comprises a cylindrical cast metal shell 15 provided with spaced internal lugs 16. The field assembly disposed within the shell, has its magnet portion A' seated against said lugs 16 and it is secured by cap screws 17. Base block 20 is integrated with said casing shell, as by cap screws 18. Each side of said shell embodies a flange provided with machined annular face 22 and with interiorly offset annular seat 23.

For clarity, one side of the structure above indicated, may be referred to as left, and the other, right, as signified by L and R respectively, in Figure 1. Cross bar 25 has its end portions secured, 25 as by cap screws 26, to the left hand seat 23 of the said casing section 15 (see Figure 1) and it is provided with a central aperture 27 the axis of which is coincident with the axis of the said field assembly. A closure of the left side of the 30 said casing section 15 consists of a circular plate 29, and sealing gasket 30 secured, as by cap screws 31, to the left hand face 22 of the said casing section. Secured to said closure plate 29, and communicating with the interior of the 35 casing, is discharge valve 32. This valve, like another and similar valve presently to be mentioned, is of the known type and construction as indicated in Figure 6. A closure plate complementary to said closure plate 29, and a cross member complementary to the said cross bar 25, 40 will be presently referred to.

A member which I designate as an arbor, embodies a cylindrical trunk 34 having at its right hand end, a shank 35, neck 36, and stem 37; and 45 at the left hand, the shank 38, neck 39, and stem 40. Provided in said trunk and being of length to extend slightly into the said shanks 35 and 38, is a smooth longitudinal radial slot 42. It is of depth slightly greater than the radius of said trunk. In line with the said slot and extending from the bottom thereof, are spaced recesses 43. Exhaust duct 44 extends from the bottom of said slot and through the arbor, with exit at the left. In a bore 45 provided in the neck 37 is a 50 tractive coil spring 46 which bears against a disk

47 that is seated against apertured plug 48 that is screwed into and which closes said bore, this structure constituting a check valve. Leading from said bore 45 is inlet duct 50 which enters the right hand end of the said radial slot 42 at a point offset from the inboard portion of said slot, as shown in Figure 6.

A machined flat bar which I designate as a vane 51, is of thickness to be retained slidingly in said radial slot 42, and it is of width slightly less than the depth of said slot. The outboard face 51a of said vane is slightly rounded in cross section. Said vane is provided at its right hand end and at a side thereof, with a port 52 which is communicable with the said inlet duct 50 and turns at a right angle and thence diagonally upwardly and has its exit at a side of the outboard face 51a of said vane.

Ports 55 which extend from the opposite side of said outboard face 51a, communicate with the aforesaid exhaust duct 44 at the bottom of the vane. In the inboard face of said vane are recesses 56 which are spaced to register with the aforesaid recesses 43 of the arbor slot. Protractive coil springs 57 seated in the recesses 43 and which extend into the recesses 56 of the said vane, urge the vane outwardly, and at the same time the said vane is capable of being pressed inwardly.

A cylinder having bore 60 of greater diameter than the diameter of trunk 34 of the arbor, embodies annular end portions 61 and 62 which are inwardly beveled to constitute cone shaped journals 63 and 64 respectively, that are eccentric to the axis of said bore.

The internal boundary lines 63a and 64a of these said journals will later be referred to. The said cylinder is integrated at its said annular end portions, with the rotor B, and axially thereof.

On the shank 35 of said arbor, is a ring 65 provided with an annular face of beveled formation to correspond with and which constitutes a bearing for the journal 63 of said cylinder. The said ring is fixedly secured to the said shank, as by a cross pin 67. A radial cut 68 in said ring is in registration with the end of the said radial slot 42 and it constitutes a guideway for the end portion of said vane.

On the other or left shank 38 of the said arbor, and flush with the vertical face of the latter, is a ring 69 similar to the one just described and which constitutes a bearing for the journal 64 at the left hand end of the cylinder. In the bore of this ring 69 is a longitudinal groove 70 in which is received a stud 71 that projects from said shank, whereby this ring 69 while being held against rotative movement, is movable longitudinally.

A pressure ring 72 lies against the outer face of the said bearing ring 69. A collar 73 is secured to said shank 38 as by a set screw 74. Between the said pressure ring and said collar, a protractive spring 75 is retained and it functions to hold the said bearing ring firmly against the face of said shank. By this arrangement there is permitted a yielding of the bearing ring 69 in an emergency, such as excessive pressure in the compression portion of the cavity presently referred to. As will be seen in Figure 1 and Figure 4, the bore 60 of said cylinder constitutes the longitudinal wall, and the bearing rings 65 and 69 constitute the end walls enclosing the void about the arbor trunk 34. This void or space so closed, is crescent shaped in cross section, is designated as cavity 76. The planes of the boundary lines 63a and 64a being slightly convergent, the cavity is of length 75

greater at one side than the other, as indicated in Figure 1. By this feature there is afforded means whereby the area D (see Figure 12) of the cavity, at one side of the partition thereof, is of decreasing dimensions longitudinally and circumferentially (producing compression of augmented increase of intensity), and at the other side S of the said partition, of increasing dimensions longitudinally and circumferentially (producing intake of augmented increase of volume).

In completing the constructing of the machine, the arbor, with the cylinder and rotor combined therewith as described, is disposed with its stem 40 in the aperture 27 of cross bar 25, the rotor assuming its position concentrically with the field assembly. The right frame member 71 is now secured in place with its end portions fastened as by cap screws 79 to the seat 23 of the casing section 15 (see Figures 1 and 3), the stem 37 of the arbor being received in aperture 78 of the said frame member. By tightening the set screws 80 in the said frame cross members 25 and 71, the arbor is fixedly secured in its position axially of the field assembly, and the rotor being free rotatively. By the urge of the springs 57, the vane is held in position constantly urged against the bore of the cylinder.

Circular casing side plate 82 having a central inlet port 83 and interiorly positioned shallow recess 84 in which is retained a sealing disk 85 of lead or the like provided with central aperture, is now disposed with its marginal portions in registration with the sealing gasket 86 and the right face 22 of said casing section 15. Upon tightening the cap screws 87, the said plate is drawn and secured to gas tight union with the casing section 15, and the central portion, at the same time, will have been drawn and secured to gas tight union with the stem 37 of the said arbor. Service valve 88 which is secured to the said plate 82 at the port 83 thereof, is for control of the gas inlet nozzle 89.

Within the casing structure, suitable lubricant at a level approximately as indicated by the broken line O—O may be had, the bearings at the cylinder journals and the bearings at the vane being oil sealed. By the construction just described, all operative parts are enclosed within a gas tight casing. Refrigerant gas is admitted through suitable conduit (not shown) at the inlet valve 88.

Operation.—Assume the rotor to be moving in the direction of the arrow (see Figure 9). The cylinder, carried as it is, in an orbit about the arbor (the axis C of the cylinder being eccentric to the axis R—A of the arbor, and the bore 60 of the cylinder being tangent to the perimeter of the arbor), the cavity 76 is moved around the arbor with each revolution of the rotor.

In what may be termed a neutral position of the several parts, as indicated in Figure 9, the line of tangency of the bore of the cylinder and the perimeter of the arbor, and the line of engagement of the outboard face 51a of the vane with said bore, are coincident.

At Figure 10, the cavity will have traveled one fourth of its stroke and will have been partitioned by the vane. At this phase, compression will have been started in the exhaust portion D of the said cavity whence the gas content thereof will be exhausted into high side of the system when the exhausting pressure is equal to or greater than is the pressure at the high side of the system, (by high side of the system being meant the interior of the casing and the conduits and appliances (not shown) connected with

the discharge valve 32; and by low pressure side of the system, being meant the appliances and conduit (not shown) connected with the inlet valve 88), the refrigerant at inlet port 83 thereby being sucked in.

At Figure 11 the said cavity will have traveled one half of its stroke, portion D decreasing in area, compressing and discharging proceeding. Portion S increasing in area, taking in more gas.

At Figure 12 the said cavity will have traveled three fourths of its stroke. At this phase, the portion D is further decreased in area. Compression will have become nearly completed; portion S is increased to nearly its maximum area, and the intake will have become nearly complete.

At Figure 9, the cavity will have traveled its full stroke, compression of the cavity content will have been completed and the content exhausted, the cavity will have become refilled with low pressure gas or refrigerant, and the vane returned to retracted position.

With each revolution of the rotor, there is repetition of the operation and functioning just described.

The function of the check valve 48 is to prevent the gas at the high pressure side from escaping into the low pressure side, at such time as the machine is off cycle. By off cycle, being meant the phase or period when the machine is static or idle.

Advantages of my invention are that the construction as an entirety is compact and strong, and it involves a minimum number of parts. The bearings for the rotor, and the bearings for the pump being one, and the said bearings also constituting the end walls of the cavity; sidewall friction is eliminated and frictional resistance is so minimized that electrical energy is materially conserved. The pump mechanism being directly combined with the rotor in the manner as described, the unit so constituted, is capable of being removed and replaced bodily, without having to do with the stator other than removing the frame member at one side thereof. In case of necessity for the removal of the field assembly, access to the interior of the casing is practicably had by the removal of either or both of the side plates, and either or both of the said frame cross members, all of the said casing and frame parts being independent of the operative parts of the machine. Throughout, my invention eliminates the need of costly special parts, and of expert machine work by service men in the field.

All of the stages in processing, and in the handling and the assembling of the several parts embodied in the invention, are relatively simple. The parallel planes of the faces of the opposed bearing rings 65 and 69 bisecting, as they do, the convergent planes of the boundaries 63a and 64a of the cylinder bore—that portion of the cavity nearest the vane 51 thereby being of lessened area both longitudinally and circumferentially, the effect is: that in travel of the cavity around the arbor, the gas therein is compressed with concentrated intensity increasing to the moment of exhaust. Thus there is a minimum amount of pressure loss. The greater bulk of the annular end portions of the cylinder being about equal to the bulk of that portion of the cylinder in which the bore is of maximum length, there is such counterbalance that there is no tendency to vibration. Also the hollow 98 between the external surface of the cylinder and the interior

surface of the annular rotor, contributes to normalcy of temperature of the moving parts. The said bearing rings also constitute a guide and support for the outboard portions of the ends, as well as the medial portions of the ends of the vane during the phase when the vane is in the pushed in or retracted position, and during the phase when the vane is moving. One of said bearing rings, namely ring 69, being yieldable longitudinally, there is no liability of interruption of operation of the pump, for the reason that any oil or incompressible liquid that might enter the cavity during the time that the machine is off cycle, is permitted to escape.

Whereas in this application, the several parts comprised in my invention, are described and illustrated in what I consider as their preferred forms, it will be understood that minor modifications may be made, within the scope of the invention as it is defined in the appended claims, without departing from the spirit or principle of the invention or sacrificing any of its advantages.

What I claim as my invention is:

1. A machine of the kind described, comprising an electric motor-field assembly, an electric motor rotor, a cylinder embodying annular end portions that are eccentric to the axis of the cylinder, are concentrically integrated with said rotor, and are beveled concentrically thereof to constitute cone shaped journals, a cylindrical arbor of diameter less than the bore of the said cylinder, and which said arbor is supported against rotation and coaxially of said rotor and at position tangentially of the said cylinder to provide a crescent shaped void thereat, the said arbor being provided with a longitudinal radial slot, there being immediately at a side of said slot an exhaust duct leading from the perimeter of the arbor and having exit at an end of the arbor, and there being an inlet duct at the other end of the arbor and leading to the opposite side of said slot and with its exit at the perimeter of the arbor, a vane loose radially in said slot, means to yieldingly urge the vane outwardly and in contact with the cylinder, and opposed beveled rings spaced upon and fastened to said arbor at positions engaged with said cone shaped journals of the eccentric end portions of said cylinder, thereby closing the ends of said cylinder, supporting it for rotative movement, and constituting said void into a crescent cavity, whereby, with each revolution of the rotor and the moving by the cylinder of the cavity around the arbor, the said cavity will have been exhausted and refilled.

2. A machine of the kind described, comprising an electric motor-field-assembly, an electric motor rotor, a cylinder embodying annular end portions that are eccentric to the axis of the cylinder, are concentrically integrated with said rotor, and are beveled concentrically thereof to constitute cone shaped journal's, a cylindrical arbor of diameter less than the bore of said cylinder, and which said arbor is supported against rotation and coaxially of said rotor and at position tangentially of the said cylinder to provide a crescent shaped void thereat, the said arbor being provided with a longitudinal radial slot, there being an exhaust duct from and an inlet duct to said slot, a vane slidable radially in said slot and being provided at a side thereof with a duct extending from an edge of the outboard face of said vane and communicating with said exhaust duct, and at the opposite side thereof being provided with a duct in registration with said inlet duct

and extending from an end of the vane and through the opposite edge of the outward face of said vane, means to urge the vane outwardly and into contact with the cylinder, and opposed beveled rings retained on said arbor to constitute bearings for said cone shaped journals and closures of the ends of the said cylinder, one of the said rings being fixedly secured to, and the other of said rings being held non-rotatively on, but yieldable longitudinally of, the said arbor.

3. Same as claim 2 plus a check valve in the inlet duct of said arbor.

4. A compression machine consisting of a gas tight casing, an electric motor field-assembly, an outlet service valve at a side of said casing, an electric motor rotor, a cylinder embodying annular end portions that are eccentric to the axis of the cylinder, are concentrically integrated with said rotor, and are beveled concentrically thereof to constitute cone shaped journals, a cylindrical arbor of diameter less than the bore of the cylinder and which said arbor is supported against rotation and coaxially of said rotor and at position tangentially of the said cylinder to provide a crescent shaped void thereat, the said arbor being provided with a longitudinal radial slot and an axial inlet passageway entering the slot at an end of the latter, a check valve in said inlet passageway, an exhaust passageway extending from the inboard zone of said slot and through the other end portion of said arbor, a vane of width slightly less than the depth of, and which is slidably radially in said slot, and is provided at an end and adjacent side thereto with a port that is communicable with said inlet passageway and has its exit at a side of the outboard face of the said vane, ports in the opposite side of said vane which are communicable with the said exhaust passageway and have their exits at the opposite side of the outboard face of said vane, springs to urge the said vane outwardly and into contact with said cylinder, opposed beveled rings retained on said arbor and constituting bearings for said journals of, and closures of the ends of the said cylinder, a service valve at the inlet side of said casing, and a union joint interconnecting said service valve with the inlet end of said arbor.

5. A pump assembly for a compression machine of the kind described, consisting of an electric motor rotor, a cylinder embodying annular end portions that are eccentric to the axis of the cylinder, are concentrically integrated with said rotor, and are beveled concentrically thereof to constitute cone shaped journals, a cylindrical arbor of diameter less than the bore of the cylinder and which is provided with axial extensions adapted to be made secure whereby the arbor is non-rotatively maintained in position coaxially of said rotor and tangentially of the said cylinder, the said arbor being provided with a longitudinal radial guideway slot, there being immediately at a side of said slot an exhaust duct leading from the perimeter of the arbor and having exit at an end of the arbor, and there being an inlet duct at the other end of the arbor and leading to the opposite side of said slot with its exit at the perimeter of the arbor, a vane loose radially in said guideway slot, means to urge the vane outwardly and into contact with said cylinder, and opposed beveled body rings spaced upon and fastened to said arbor at positions engaged with the cone shaped journals of the said cylinder.

6. A pump mechanism of the kind described, comprising an electric motor rotor having a cylind-

rical bore, a cylinder embodying annular end portions that are eccentric to the axis of the cylinder, are integrated with the bore of said rotor, and are beveled concentrically thereof to constitute cone shaped journals, a cylindrical arbor of diameter less than the bore of said cylinder, embodying axial extensions, and being provided with a longitudinal radial guideway slot, an exhaust duct at a side of said slot leading from the perimeter of and through the arbor, an inlet duct leading from an end of the arbor and to the opposite side of said slot and having exit at the perimeter of the arbor, a vane slidably radially in said slot, means to yieldingly urge the vane outwardly and to contact with said cylinder, opposed ring shaped body members spaced upon and fastened non-rotatively to said arbor at positions engaged with said cone shaped journals, one of said body members being movable longitudinally of the arbor, and each of said body members being provided with a recess to receive slidably the outboard portion of an end of the said vane, and means adjacent to the movable ring shaped body member to yieldably hold it against the adjacent cylinder bearing, whereby the arbor is positioned axially of the bore of said rotor and tangentially of the bore of said cylinder, the ends of the cylinder are closed, the cylinder and rotor are coordinated in free rotative relation to said arbor, guideways are constituted for the outboard end portions of the said vane, and there is yieldability of the union of the said body members and the said cylinder.

7. A compression machine comprising a gas-tight casing, an outlet service valve at a side thereof, an electric motor field-assembly secured within the said casing, a support member adjacent the interior face of each side wall of the said casing, an electric motor rotor, a cylinder embodying annular end portions that are eccentric to the axis of said cylinder, are concentrically integrated with said rotor, and are beveled concentrically thereof to constitute cone shaped journals, a cylindrical arbor of diameter less than the bore of said cylinder and which embodies axial extensions which are received in said support members, means to secure said extensions in said support members to hold said arbor against rotative movement and in position coaxially of said rotor, the said arbor being provided with a longitudinal radial guideway slot, there being an exhaust duct immediately at the side of said slot and leading from the perimeter of the arbor and having exit at an end of said arbor, and there being an inlet duct at the other end of the arbor and leading to the opposite side of said slot and with its exit at the perimeter of the arbor, a vane slidably radially in said guideway slot means to hold the vane yieldingly in contact with the bore of said cylinder, a ring shaped body member fastened non-rotatively to said arbor at each end of the cylinder to engage the cone shaped journal thereat, one of said body members being movable longitudinally of the arbor, and each of said body members having a recess to receive slidably the outboard portion of an end of said vane, and means adjacent to the movable ring shaped body member to yieldably hold it against the adjacent cylinder journal, a check valve in the inlet duct of said arbor, and a shut-off valve communicable with said check valve at the inlet side of said gas-tight casing.

CHESTER B. CURRY.
